COMBINED COOLING AND STORAGE RACK FOR PIES AND THE LIKE

Signe O. Callender, P.O. Box 74, Eagle, Idaho 83616

Filed May 21, 1965, Ser. No. 85,394

Term of patent 7 years

(Cl. D44—29)

FIGURE 1 is a front perspective view of the combined cooling and storage rack for pies and the like embodying my new design; and

I claim:

The ornamental design for a combined cooling and storage rack for pies and the like, as shown.
